United States Patent Office

Des. 191,129
Patented Aug. 15, 1961

191,129

LUMINAIRE

Raoul E. Rodriguez, Chicago, Ill., and Robert H. Madding, Little Rock, Ark., assignors to McGraw-Edison Company, Milwaukee, Wis., a corporation of Delaware

Filed Oct. 31, 1960, Ser. No. 62,676

Term of patent 14 years

(Cl. D48—31)

Fig. 2

Fig. 1

Fig. 3

Fig. 4

FIG. 1 is a side elevation of a luminaire embodying our new design;

FIG. 2 is a top plan view thereof;

FIG. 3 is a front elevation thereof; and

FIG. 4 is a rear elevation thereof.

The dominant features of our new design reside in the portions shown in full lines.

We claim:

The ornamental design for a luminaire, as shown and described.
